CLAIM

The ornamental design for a driving unit for a camera lens, as shown and described.

DESCRIPTION

FIG. 1 is a top perspective view of a driving unit for a camera lens showing our new design.

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The broken lines shown in the drawings depict portions of the driving unit for a camera lens that form no part of the claimed design. The dot-dash lines shown in the drawings depict the boundary of the claim and form no part of the claimed design.
